(57) **CLAIM**

I claim the ornamental design for a brush cutter, as shown and described.

DESCRIPTION

FIG. 1 is a top view of the brush cutter;

FIG. 2 is a left side perspective view of the brush cutter shown in FIG. 1;

FIG. 3 is an enlarged partial left side perspective view of the brush cutter shown in FIG. 1;

FIG. 4 is an enlarged partial right side perspective view of the brush cutter shown in FIG. 1;

FIG. 5 is a rear view of the brush cutter shown in FIG. 1;

FIG. 6 is an enlarged partial rear view of the brush cutter shown in FIG. 1, with the pull string shown rotated 90 degrees; and,

FIG. 7 is an enlarged partial front perspective view of the brush cutter shown in FIG. 1.

The views of FIGS. 3, 4, 6 and 7 are shown fragmented for clarity of illustration.
